UNITED STATES PATENT OFFICE.

OSWALD H. THOMPSON, OF PHILADELPHIA, PENNSYLVANIA.

AWNINg-LIFTER.

SPECIFICATION forming part of Letters Patent No. 519,780, dated May 15, 1894.

Application filed February 15, 1893. Serial No. 462,446. (No model.)

To all whom it may concern:

Be it known that I, OSWALD H. THOMPSON, a citizen of the United States, residing at Philadelphia, in the county of Philadelphia, State 5 of Pennsylvania, have invented certain new and useful Improvements in Awning-Lifters; and I do declare the following to be a full, clear, and exact description of the invention, such as will enable others skilled in the art to 10 which it appertains to make and use the same.

My present invention relates to that class of devices whereby awnings are raised by spring pressure.

It is the especial object of the improvement 15 hereinafter set forth to provide for window awnings a more convenient and inexpensive appliance for this purpose especially adapted to be secured to the upper part of the window within the awning and, when the device is set 20 in motion or when the awning is released, to lift the latter to its closed or upright position against the side of the building without the requirement of any exertion upon the part of the operator.

25 With such object in view, my invention consists in the parts and combination thereof hereinafter particularly set forth and claimed.

In order to make my invention more clearly understood, I have shown in the accompanying 30 drawings means for carrying it into practical effect, without however limiting the improvement in its useful applications to the particular construction, which, for the sake of illustration, I have delineated.

35 In said drawings—Figure 1 is a vertical sectional view showing the portion of a building with its window frame, and an awning applied thereto and provided with a raising or lifting device embodying my improvements. 40 Fig. 2 is a front view of the lifter secured in place upon the upper portion of the window frame. Fig. 3 is a transverse vertical sectional view of the same. Fig. 4 is a longitudinal vertical sectional view. Fig. 5 is a 45 similar view of a still further improved form of my invention. Fig. 6 is a transverse sectional view of the same.

Referring to the drawings:—1 indicates the portion of a building having a window opening 2 to the frame of which is pivotally secured a U-shaped awning frame 3 of ordinary character carrying an awning 4 secured there-

to and secured in the ordinary manner at its upper end to the window frame.

5 is a yoke provided with eyes 6 whereby it is suspended from hooks 7 inserted in the upper portion of the window frame. In the lower ends of said yoke are formed bearings which are square or otherwise adapted to receive and prevent the rotation of a shaft 7^a 6c mounted therein. On said shaft is mounted a rotary and hollow drum 8 on which is adapted to be wound and taken up a cord or chain 9 which is secured at one end to the drum and at its lower end to the awning frame 3 at or 65 near its middle. Another rope or cord 10 also secured to said awning frame and extending inward to the window sill serves to draw down or let up the awning. On the window sill the rope 10 is secured in any suitable catch or 70 holder. Within the drum 8 is inclosed a strong spring 11 of spiral form having its inner end secured to the shaft 7^a by a pin 12, and having its outer end provided with an eye 13 through which passes a longitudinal bolt 75 or rod 14 secured in the heads of the drum.

When it is desired to shade the window the awning and frame are drawn down by means of the rope 10 in the position shown in Fig. 1, and the rope secured in the catch upon the 80 window frame. When it is desired to have the awning elevated the rope 10 is released from the catch whereupon the spring 11 will uncoil with sufficient force to wind up the rope 9 and lift the frame 3 with the awning 85 into a position parallel with the face of the window frame and building.

It will be observed that this device is ready and capable of instant attachment to any ordinary window frame and awning, and, 90 when in place beneath the upper portion of the window frame and within the awning is entirely protected from the weather and also from observation, leaving the windows and front of the building entirely free from any 95 objectionable disfigurement.

The foregoing is a description of a simple form of my improvement, but I prefer to embody it in the form indicated in Figs. 5 and 6, wherein the yoke is provided with a rotary shaft, the casing of the spring is non-rotary and secured together with one end of the spring to one leg of the yoke by means of the pin or bolt 14, and the said shaft is provided

with a windlass independent of the spring casing, and also with a ratchet wheel 15 secured rigidly to the shaft or windlass and engaged by a pawl 17 pivotally mounted upon 5 the upper portion of the yoke at 18. To raise the awning the rope 10 is given a slight downward pull which will cause the pawl 17 to disengage the ratchet wheel, when the latter is caused by the spring to rotate with sufficient rapidity to prevent the pawl again engaging with the ratchet wheel.

Having thus described my invention, what I claim is—

15 In a lifter for window awnings the combination with the awning frame of a yoke suspended within the window beneath the upper

transverse portion thereof, a shaft mounted and rotary in said yoke, a drum on said shaft having a rope or chain connected with the awning frame, a stationary casing mounted 20 on said shaft and secured to said yoke, a spring within said stationary casing and connected therewith and with said shaft, a ratchet wheel on the shaft, and a pawl or dog mounted on said yoke and engaging the 25 ratchet wheel, substantially as set forth.

In testimony whereof I affix my signature in the presence of two witnesses.

OSWALD H. THOMPSON.
